F. M. NAYSMITH

ARCH RAISING MACHINE

Filed Jan. 19, 1924

Patented July 21, 1925.

1,546,506

UNITED STATES PATENT OFFICE.

FRANK M. NAYSMITH, OF KANSAS CITY, MISSOURI.

ARCH-RAISING MACHINE.

Application filed January 19, 1924. Serial No. 687,241.

To all whom it may concern:

Be it known that I, FRANK M. NAYSMITH, a citizen of the United States, residing at Kansas City, in the county of Jackson and 5 State of Missouri, have invented certain new and useful Improvements in Arch-Raising Machines; and I do declare the following to be a full, clear, and exact description of the invention, such as will enable others 10 skilled in the art to which it appertains to make and use the same, reference being had to the accompanying drawings, and to the figures of reference marked thereon, which form a part of this specification.

15 This invention relates to an arch raising machine and it is particularly adapted for raising fallen arches by raising the metatarsal bones, the machine being used at convenient intervals so that after a number of 20 treatments, the articulation will be corrected and the bones of the foot will remain in their normal positions. The device is so constructed that the patient may operate it in an easy manner so that home treatment may 25 be provided by using my invention.

The simplicity of the structure as well as the novel manner of operating the invention will be apparent by reference to the following description in connection with the 30 accompanying drawings in which—

Fig. 1 is a perspective view of an arch raising machine constructed in accordance with my invention.

Fig. 2 is a cross sectional view through the 35 bridge bar for raising the arch.

Fig. 3 is a bottom perspective view of the machine, the operating lever being shown in fragmentary perspective and parts of the straps being broken away, and

40 Fig. 4 is a perspective view of the part of the base showing the pad in perspective with the bridge bar in position to raise it.

The base 1 may consist of an elongated block with a cut-a-way portion 2 at its rear 45 end and grooves 3 and 4 intermediate its ends. The cut-a-way portion 2 receives an ankle strap 5 which is held in place by the L-shaped cleats 6 and 7 which span the cut-a-way portion to hold the strap 5 to the base 50 as will be clearly seen by reference to Fig. 3.

Longitudinal bars 8 and 9 bridge the 55 grooves 3 and 4 to hold the strap 10 in the grooves, it being observed that the strap has a double lap, that is, it passes from groove 3 around the foot in the groove 4 and then the

end is fastened by a buckle connection as at 11. The edges of the base or block are in-cut far enough to receive the strap 10 so that the operating lever 12 may swing on its pivots 60 13 and 14 without coming into contact with the straps.

The operating lever has two side bars 15 and 16 connected at their upper ends by a handle 17 which may be grasped by the 65 operator to swing the lower edges of the lever on the pivots 13 and 14. The lever constitutes an actuator with the lower ends of the side bars 15 and 16 turned into elbows or right angular extensions 18 and 19 which 70 may press upward on the bridge or arch bar 20 consisting of the metal bar having depending ends 21 and carrying a wooden bar 22 which contacts with a flexible pad 23 fastened at its respective ends 24 and 25 to the 75 block and intermediate its ends to the bar 22 so that when the arch bar is raised the pad will press against the metatarsal bones and raise the arch.

Of course in order to properly raise the 80 arch the foot must be strapped onto the base 1 by the straps 5 and 10 as shown in Fig. 1. The operator may then push forward on the upper end of the actuator or lever 12. The outward swinging motion of the lever 85 is variable of course, depending upon the patient being treated. If a very flat arch is to be reconstructed the initial movements of the lever will be comparatively slight until towards the last after the arch begins to assume its proper form, then the lever can be 90 drawn very far forward. In all instances the lever should be drawn as far forward as possible without causing too much pain to the patient and held there for an appreciable time to allow the bones to accommodate themselves to the new position, and ultimately the bones can be pushed back to 95 their natural positions.

Due to the position of the elevator bar, 100 it will be capable of raising any one or all of the metatarsal bones, dependent upon the position of such bones during treatment.

What I claim and desire to secure by Letters-Patent is:

1. In an arch-raising machine, a foot rest, means for securing the foot to the rest, a transverse arch elevating bar carried by the rest, having an upper edge portion to engage under the arch of the foot, an actuator therefor, and a flexible pad of greater width than the width of the bar secured 105 110

over the bar to protect the foot from contact with the bar.

2. An arch restoring means comprising a foot rest, means for securing the foot to the rest, the rest having a transverse slot, a transverse bar in the slot, projections on the end of the bar and an actuator pivoted to the side of the foot rest and having projections engaging under the projections on the 10 end of the bar for raising it.

3. An arch restorer device comprising a foot rest, spaced foot securing means carried by the rest, an arch elevating bar loosely mounted in the slot in the rest and having 15 end projections and a lever pivoted to the side of the foot rest and having right angular projections for engaging under the projections on the foot rest.

4. An arch restoring means comprising a 20 foot rest, straps for securing the foot to the rest, a vertically movable transversely disposed bar mounted in the foot rest, a pad over the bar, projections on the end of the bar and an elbow lever having a long arm and a short arm, the short arm resting under one of the projections on the bar to raise it.

5. An arch elevating means comprising a foot rest, means for securing the foot to the

rest, an arch elevating bar transversely of the rest having projections, a flexible pad above the arch elevating bar and an elbow lever pivoted to the foot rest for raising the bar.

6. In an arch restoring device, a foot rest 35 having a slot, means for securing the foot to the rest, an arch elevating bar in the slot, mounted for vertical movement and a lever for raising said bar.

7. In an arch restoring device, a foot rest 40 having a slot, means for securing the foot to the rest, an arch elevating bar in the slot, mounted for vertical movement, and a lever for raising said bar, said lever being formed at its end with an elbow to provide a toe to 45 engage under the bar.

8. In an arch restoring device, a foot rest having a slot intermediate its ends, a transverse bar vertically slidable in said slot, an operating lever for said bar, pivoted to the 50 foot rest, a flexible pad secured to the foot rest and bridging the bar, an ankle strap carried by the rest and a strap carried by the rest for securing the forward portion of the foot thereto.

In testimony whereof I affix my signature.

FRANK M. NAYSMITH.
